CONSTRUCTION OF FIRE PROOF BUILDINGS.

No. 448,048.

Patented Mar. 10, 1891.

UNITED STATES PATENT OFFICE.

ERNEST V. JOHNSON, OF CHICAGO, ILLINOIS.

CONSTRUCTION OF FIRE-PROOF BUILDINGS.

SPECIFICATION forming part of Letters Patent No. 448,048, dated March 10, 1891.

Application filed November 3, 1890. Serial No. 370,150. (No model.)

To all whom it may concern:

Be it known that I, ERNEST V. JOHNSON, a citizen of the United States, residing in Chicago, in the county of Cook and State of Illinois, have invented a new and useful Improvement in the Art of Constructing Fire-Proof Buildings, of which the following is a specification.

My invention relates to the construction of fire-proof buildings, and more particularly to the construction and means of supporting the tile structure composing the ceiling and floors of the separate rooms or compartments.

Heretofore the ceiling and floor tile structure has been supported upon a series of parallel metallic I-beams, placed usually at a distance of from five to seven feet apart, (more or less,) which I-beams rest upon supporting-girders extending between the posts or structural columns of the building. As all the beams supporting the tile rest upon the girders, the total weight is of course transferred to the girders, thus rendering it necessary to make the girders very strong and heavy. Heretofore, also, the space above the tile to the level of the upper edge of the beams is usually filled in solid with concrete or other equivalent material, upon which the flooring, whether of wood boards or flooring-tile, is laid. The whole floor area between the columns thus has a concrete filling above the tile of about equal depth or thickness throughout. A serious objection has been experienced in the practical use of this old construction of tile floor and ceiling, owing to the great weight of the thick solid concrete filling on top of the tile and to the numerous parallel steel beams which were necessarily employed to support the tile and transfer the weight of the same to the girders. This excess in weight of floor construction is a matter of great moment in the practical construction of high fire-proof buildings now being commonly erected in most large cities.

The object of my invention is to provide a simple, strong, durable, and comparatively cheap ceiling and floor tile structure which shall be very much lighter in weight than the construction heretofore generally in use, and by means of which, also, both the objectionable weight and the cost of the parallel beams, which have heretofore been used to

support the tile and transfer the weight of the same to the girders, may be entirely dispensed with.

My invention consists in the novel devices and novel combinations of parts and devices herein shown and described, and more particularly pointed out in the claims.

In the accompanying drawings, which form a part of this specification, and in which similar letters of reference indicate like parts, Figure 1 is a plan view of a device embodying my invention, the same showing a portion or compartment of a building between a single set of four columns. This view is partly in horizontal section and shows in part different layers or strata of the floor and ceiling structure. Fig. 2 is a vertical section taken on line 2 2 of Fig. 1. Fig. 3 is an enlarged section taken on line 3 3 of Fig. 1. Fig. 4 is a section on line 4 4 of Fig. 1. Fig. 5 is a section on line 5 5 of Fig. 1. Fig. 6 is a detail vertical sectional view of the concrete arch supporting or forming device, the same being a section taken on line 6 6 of Fig. 1. Fig. 7 is a section taken on line 7 7 of Fig. 1. Fig. 8 is a perspective view of a clamp device which may be used to hold the concrete arch forming or supporting device in place while the concrete or cement is becoming set.

In the drawings, A A represent four columns of a building, the same being usually iron or steel columns.

B B are four girders or beams extending between and supported by the four columns. These girders or beams are or should be made of steel and of an I-form. Tie-rods C C, extending between the opposite beams B B near the middle thereof and secured thereto by bails or clips C' C', may be employed to stiffen the girders, if necessary or desired. I also provide or may provide brace tie-rods C² C², extending diagonally across the corners, the same being attached to the adjacent girders B B by bails or clips C³ C³. The tie-rods C C² may or may not be used. They are chiefly useful in connection with the outside girders of the building, as the interior girders will receive a bracing-support from the adjacent sections of the building.

D is a self-supporting cloister-arch hollow-tile structure extending between and carried

by the four girders or beams B. This cloister hollow-tile arch D is furnished with or composed in part of four diagonal ribs d, extending from the center or keystone E to the 5 four corners of the structure. The hollow rib-tiles d have shoulders d' to receive and support the adjacent intermediate hollow tiles d². The tiles d², which rest upon the ledge or shoulder d' in the rib-tile d, have angle-faces d³ corresponding to the angle of the ribs d. The marginal tiles d⁴, which fit upon the webs b of the beams B, have shoulders or recesses d⁵ to fit the webs. These marginal tiles d⁴ are also furnished with projecting inclined faces d⁶, to receive and support the intermediate beam-tile F, which covers and protects the lower flange of the beams or girders B. The key E is preferably made of tile; but it may be made solid instead of hollow. 10 The tile in the line of the tie-rod C may be grooved, notched, or perforated to give room for the rod.

H represents the concrete, cement, or other equivalent filling above the tile cloister arch D. This filling H is made in the form of a series of hollow ribs or arches for the purpose of diminishing its weight, and at the same time bringing the level of the floor up to the desired height. The series of arches 25 or hollow ribs h of this concrete filling H extend or should extend at right angles to or across the curvature of the four triangular sections of the cloister-arch D, as is clearly indicated in Fig. 1 of the drawings, so that 30 the concrete-filling structure may be strongest in the direction that each section of the cloister tile arch D is weakest, the strength of the one re-enforcing the strength of the other, thus adding to the combined strength of the 35 two in the structure as a whole. Owing to the curvature of the cloister tile arch D, it will be observed that the concrete-filling H is much thinner near the keystone or center of the structure than near the corners or margin 40 of the same, and that the hollow channels or arches h in the concrete filling H are correspondingly flattened toward the center. This is clearly indicated in the drawings in 45 Fig. 2, and also by a comparison of the sections, Figs. 6 and 7, which show the form of the channels or arches at different points.

The most convenient method I have found for constructing this hollow or arched concrete filling H is to place on top of the cloister tile arch D, after the same is put up, a series 55 of tapering semi-cylindrical arch-forming center devices K. These may be made of any suitable material—as, for example, thin sheet-iron or stiff straw-board. If these arch-forming devices are made of straw-board or such material, they may be preferably saturated or coated with pitch or tar or like material. The lower limbs of the adjacent arch-forming devices K may be held in place by clips k, 60 placed at intervals.

The purpose of the device K is simply to shape and support the concrete or cement filling H

while it is being tamped in place and until the cement becomes set. The devices K are simply to shape the arches or channels h and 70 not to give any permanent strength or support to the structure as a whole. These devices K may therefore be formed of any substance desired, and it is immaterial whether it be of a durable nature or not.

M represents the flooring, and m the strips laid in the concrete filling, and to which the flooring-boards may be nailed in cases where the surface-floor is of wood.

The rib-tiles d projecting below the soffit 80 of the arch D make an ornamental finish to the cloister-arch, and the ceiling-plastering may be done directly upon the surface of the tile, or the same may be otherwise decorated.

If it is desired to have a flat ceiling, it may 85 be suspended from the arch D in the usual manner.

I claim—

1. In a building, the combination, with four supporting posts or columns, of girders or beams extending between said posts, a cloister hollow-tile arch ceiling and floor structure extending between and supported by said girders or beams, said girders or beams being secured together at the corners, so that each parallel pair thereof serves to bind or tie the other parallel pair together, whereby they serve at the same time to support the weight of the arch and to resist its lateral thrust in all directions, substantially as specified.

2. In a building, the combination, with four supporting posts or columns, of girders or beams extending between said posts, a cloister hollow-tile arch ceiling and floor structure extending between and supported by said girders or beams, and a concrete filling above said cloister tile arch, said girders or beams being secured together at the corners, so that each parallel pair thereof serves to bind or tie the other parallel pair together, whereby they serve at the same time to support the weight of the arch and to resist its lateral thrust in all directions, substantially as specified.

3. In a building, the combination, with four supporting posts or columns, of girders or beams extending between said posts, a cloister tile arch ceiling and floor structure extending between and supported by said girders or beams, and a concrete filling above said cloister tile arch, said concrete filling having a series of hollow channels or arches, said girders or beams being secured together at the corners, so that each parallel pair thereof serves to bind or tie the other parallel pair together, whereby they serve at the same time to support the weight of the arch and to resist its lateral thrust in all directions, substantially as specified.

4. In a building, the combination, with four supporting posts or columns, of girders or beams extending between said posts, a cloister hollow-tile arch ceiling and floor

structure extending between and supported by said girders or beams, and a concrete filling above said cloister tile arch, said concrete filling having a series of hollow channels or 5 arches extending in the direction of the curvature of each triangular section of said cloister tile arch, substantially as specified.

5. The combination, with the four beams or girders B, of the cloister hollow-tile arch D, 10 having four diagonal ribs d, composed of tile furnished with shoulders or ledges d' to engage the adjacent tile, substantially as specified.

6. The combination, with the four beams or 15 girders B, of the cloister hollow-tile arch D, having four diagonal ribs d, composed of tile furnished with shoulders or ledges d' to engage the adjacent tile, the marginal tile d⁴, having shoulders or recesses d⁵ to fit the webs 20 of said girders or beams B, substantially as specified.

7. The combination, with the four beams or girders B, of the cloister hollow-tile arch D, 25 having four diagonal ribs d, composed of tile furnished with shoulders or ledges d' to engage the adjacent tile, the marginal tile d⁴, having shoulders or recesses d⁵ to fit the webs 30 of said girders or beams B, and the intermediate tile d², fitting on said ledges d' and having inclined faces d³, substantially as specified.

8. The combination, with four supporting girders or beams B, of a cloister hollow-tile arch D, having marginal tile d⁴, furnished with inclined ledges d⁶, and a beam covering 35 and protecting tile F, supported by said inclined ledges d⁶, substantially as specified.

9. The combination, with four girders or beams B, of a cloister tile arch supported thereby, and a tie-rod C, extending between 40 opposite beams B B, substantially as specified.

10. The combination, with four girders or beams B, of a cloister hollow-tile arch supported thereby, and a tie-rod C, extending be-

tween opposite beams B B and bails or clips C', substantially as specified. 45

11. The combination of four girders or beams B with a cloister hollow-tile arch supported thereby and corner tie-rods C², substantially as specified.

12. The combination of four girders or 50 beams B with a hollow-tile arch floor and ceiling structure, and a concrete filling above the same furnished with or made in the form of a series of hollow channels or arches, said girders or beams being secured together at the 55 corners, so that each parallel pair thereof serves to bind or tie the other parallel pair together, whereby they serve at the same time to support the weight of the arch and to resist the lateral thrust in all directions, sub- 60 stantially as specified.

13. The combination, with a tile arch floor and ceiling structure, of a concrete filling above the same furnished with or made in the 65 form of a series of hollow channels or arches and arch-forming devices K, substantially as specified.

14. The combination, with a tile arch floor and ceiling structure, of a concrete filling above the same furnished with or made in the 70 form of a series of hollow channels or arches, and arch-forming devices K and clamps or clips k, substantially as specified.

15. The combination, with four supporting beams or girders, of a cloister hollow-tile arch 75 supported thereby, and a concrete filling having a series of hollow channels or arches extending from each side toward the center and tapering or diminishing from their outer toward their inner ends, substantially as speci- 80 fied.
